UNITED STATES PATENT OFFICE.

JOHN J. DAHLSTROM, OF AMITE, LOUISIANA.

COLLAPSIBLE CRATE.

1,353,030.

Specification of Letters Patent. Patented Sept. 14, 1920.

Application filed May 13, 1918, Serial No. 234,204. Renewed February 7, 1920. Serial No. 357,015.

To all whom it may concern:

Be it known that I, JOHN J. DAHLSTROM, a citizen of the United States, residing at Amite, in the parish of Tangipahoa and 5 State of Louisiana, have invented certain new and useful Improvements in Collapsible Crates; and I do hereby declare the following to be a full, clear, and exact description of the invention, such as will enable others 10 skilled in the art to which it appertains to make and use the same.

My present invention relates to improvements in collapsible crates, and it is intended to provide a crate of cheap and simple construction which may be quickly and readily set up or knocked down, may be manufactured and sold at small cost, is substantial in construction and safe in use; and which may be collapsed and safely shipped in the 20 collapsed condition when desired and may be readily returned to the proper position for use.

A further object of the invention is to provide a crate which may be quickly opened 25 for the purpose of inspection, or for the removal of the contents thereof, and quickly closed again; and in which the contents may be readily protected by a suitable seal if desired.

30 My invention is more especially intended to provide an improvement upon the crate shown in my earlier Patent No. 1,120,693, granted December 15, 1914, and entitled Folding crate.

35 My invention will be more fully understood after reference to the accompanying drawings, in which similar parts are indicated by similar reference symbols throughout the several views, and in which:—

40 Figure 1 is a perspective view showing the crate in the set up and closed position, the contents of the crate being omitted for the sake of clearness in the drawings.

Fig. 2 shows a vertical section along the 45 line 2—2 of Fig. 1, and looking in the direction of the arrows.

Fig. 3 is a perspective view of one corner of the top of the crate showing the lid in the closed position and with the locking strip 50 removed.

Fig. 4 is a similar view to Fig. 3, but shows the locking strip inserted.

Fig. 5 is a plan view of the top of the 55 crate, on a smaller scale, as detached from the crate.

Fig. 6 shows the crate in the collapsed or knocked down position.

Fig. 7 shows the preferred form of hinge used in the construction of the crate.

Fig. 8 shows a section along the line 8—8 60 of Fig. 7, and looking in the direction of the arrows; and

Fig. 9 is a detail showing the mode of connecting the end of the hinge to the crate.

The crate when set up is rectangular in 65 form, and consists primarily of the two side frames A and A', the end frames B and B' connected together by the hinges D, and the detachable top and bottom pieces E and E', to which may be added a locking strip F and 70 a suitable seal which will be hereinafter described.

The side frames A and A' are preferably composed of wooden strips a, to which are fastened the boards a', and the end frames B 75 and B' preferably comprise similar strips b connected together by the boards b' to form an open structure.

These side and end frames are hinged together by the hinges D, as shown in detail in 80 Figs. 7, 8 and 9, which comprise single loops of wire bent over near the ends and sharpened, as at d, and having their central portions bent to project inwardly, as at d', to engage the cover of the crate, as will be hereinafter described.

The bottom E' of the crate may consist of a single thin board, or it may be of open structure similar to the sides. This is inserted in the crate, and its corners rest on the 90 lower hinges, when the parts of the crate are in the open position, as shown in Figs. 1 and 2.

The cover E of the crate may also be made of a single thin sheet of wood, or other like 95 material, e, or it may be of open work like the sides and ends of the crate.

Extending transversely across the top of this cover are the cross pieces e', which have projecting ends e² adapted to rest on the upper part of the sides of the crate.

One end of the cover E is preferably reinforced, as by the fixed slat or strip e³, and the opposite end has its edges cut away, as at e⁴, to permit the clearance of the corners 105 of the cover from the upper corner hinges of the crate.

F represents a locking slat or strip which is used to lock the cover in place, as indicated in Figs. 1 and 4.

G represents an adhesive strip which may be pasted across the locking strip and attached to the crate as shown in Figs. 1 and 4 to effectually seal the same, so that the consignee may know whether or not the contents of the crate have been tampered with when it reaches its destination. An additional seal H may be added if desired.

When not in use, or when shipped empty, 10 the crate may be folded down to the position shown in Fig. 6 with the top and bottom pieces E and E' inserted between the parallel side frames A and A'.

To set up the crate remove the top and 15 bottom pieces from the knocked down package, then swing the end frames B and B' between the side frames A and A' to form a rectangle, and then insert the bottom piece E' which will rest on the bottom corner 20 hinges D. The crate is now ready for its contents.

After the contents have been placed in the 25 crate the cover may be applied by inserting the squared end of the cover under the corner hinges D at one end of the crate and swinging down the opposite end of the cover until the cut away portions e⁴ pass between the opposite corner hinges D, at which time the ends of the slats e² secured to the top of 30 the cover will rest on the strips a at the top of the side frames A and A'.

Now to lock the cover in place, insert the locking strip F sidewise, springing it under 35 the locking lugs d' of the corresponding corner hinges D.

The resiliency of the end of the cover E and of the strip F will cause said strip to 40 press up against the lugs d' of the hinges and will firmly hold the locking strip against accidental displacement incident to the handling or transportation of the crate.

The locking strip may if desired be 45 marked with the name of the goods and of the shipper and the consignee; but if preferred these may be shown on a separate strip of paper, or the like, pasted partly over the locking strip and the adjacent portion of the crate, as shown most clearly in Fig. 4, so that the crate cannot be opened unless 50 this adhesive strip be removed or torn. If desired, an additional seal may be provided for the locking strip, such as the ordinary freight car seal H.

In order to remove the locking strip from 55 its crate, break the seal H, press down the ends of the locking strip, so as to clear the lugs d' of the adjacent hinges, and then re-

move the locking strip, tearing the paper seal.

The ends d of the hinged loops D are 60 preferably tapered, as shown in Figs. 7, 8 and 9, and pass through holes bored in the reinforcing strips of the end or side frames, and the ends are then preferably bent over, as shown at d^o. 65

Thus there are no projecting ends to catch in adjacent crates, or in the clothing of the man or woman handling the crate; at the same time the loops can be very readily inserted and secured in place, and should 70 it be desired to break up the crate for any reason the said loops may be very readily removed.

The lugs d' of one pair of the hinges will 75 hold the locking strip F against accidental displacement; and the similar lugs of the other hinges will tend to bite into the corners of the top and bottom pieces, steadyng the same in place, and preventing any shaking around of the top and bottom pieces 80 when the crate is empty or only partly filled.

It will be obvious that various changes 85 might be made in the herein described construction, and in the combination and arrangement of parts which could be used without departing from the spirit of my invention.

Having thus described my invention what I claim and desire to secure by Letters Patent of the United States is:—

A collapsible crate comprising rectangular side frames and rectangular end frames, with a reinforcing strip at the top and bottom of each of said frames, with hinges in the form of loops, each having its central 95 portion provided with an inwardly projecting lug, connecting the adjacent ends of said reinforcing strips, a bottom piece adapted to slip into the interior of the crate and to have its four corners rest upon the lower 100 hinges, a cover provided with reinforcing strips extending across the same and projecting beyond the edges thereof, and adapted to rest upon the reinforcing strips at the sides of the crate, two adjacent corners of 105 said cover being cut away to pass clear of the corresponding hinges of the crate, and a locking slat adapted to fit over the cut-away end of said cover and to engage beneath the adjacent hinges and to be normally locked 110 in place by the lugs on said hinges, substantially as described.

In testimony whereof, I affix my signature.
JOHN J. DAHLSTROM.
